UNITED STATES PATENT OFFICE.

DONALD L. WOLF AND ROY G. KEIL, OF DENISON, IOWA.

RADIO CENTRAL-STATION SYSTEM.

Application filed January 20, 1926. Serial No. 82,399.

This invention relates to a new and improved radio central station system and more particularly to a system whereby radio reproducers located at a distance from a plurality of differently tuned receiving sets may be selectively connected to one of such sets. Radio sets capable of receiving distant stations consistently and efficiently are expensive pieces of apparatus with a considerable maintenance expense and requiring skilled tuning and operation in order to procure the best results. A further difficulty with the use of a plurality of such sets in congested districts and in large apartment houses and hotels lies in the fact that improperly operated sets may reradiate and cause interference with the reception by neighboring sets, or sets having antenna located within a considerable distance of the reradiating set.

It is an object of the present invention to provide a method and apparatus whereby subscribers to a radio distributing system, or tenants in a large building may be provided with radio programs of their own selection without the necessity for the installation, maintenance and expert operation of individual receiving sets.

It is an additional object of this invention to provide apparatus whereby the subscriber may quickly and easily select the desired station for reproduction through his local reproducer.

Other and further objects will appear as the description proceeds.

We have illustrated somewhat diagrammatically in the single figure which constitutes the accompanying drawing one form of construction which our invention may take. A plurality of radio receiving sets A—B—C—D and E are provided at some suitable central location, these sets being provided with a suitable antenna system which has not been shown. The sets are all capable of being independently tuned and may be handled by a single expert who can operate them for the highest efficiency.

The battery sides 11, 12, 13, 14 and 15 of the output circuits of the receivers join in a common wire 16 from which the wire 17 leads to the jack 18 at one local station. The wire 19 leads from the wire 16 to the jack 20 at another local station and it is obvious that as many other local stations as desired may be similarly connected. The opposite side 55 of the jack 18 is connected to the variable resistance 21 which is controlled by the mov-

able arm 22. The arm 22 is connected by wire 23 with the local battery 24. The solenoid 25 is connected across the wires 17 and 23, so as to include the battery 24 and resistance 21 in the circuit through the solenoid and reproducer 26.

The armature 27 of the solenoid is normally held at its limit of outward movement by the spring 28. In this position, the cross arm 29 is out of contact with any of the switch points. The switch 30 is provided with a plurality of points 31, all connected to the wire 23 and opposite these points 31 it is provided with a plurality of points 32, 33, 34, 35 and 36 connected to the plate side of the output circuits of the receiving sets A to E, respectively.

The reproducer 37 is provided with a solenoid 38 and switch 39 exactly similar to the arrangement just described in connection with the lines to the reproducer 26. Obviously, any desired number of reproducer circuits may be connected to the receiving sets in the same manner and any desired number of receiving sets may be incorporated in the central station.

It will be observed that with the plug out of the jack 18, the circuit, which includes the battery 24 and solenoid 25, is broken and, therefore, the spring 28 will carry the solenoid switch to its outermost position, out of contact with any of the contacts connected to the receiving sets. When the plug is inserted in the jack, the circuit is completed through the solenoid and with the resistance switch at the left limit as shown in switch 21 with all of the resistance cut in, the flow through the solenoid will be so limited as only to draw the armature into its outermost switch position, which connects the wire 23 with the contact 32 connected to receiving set A. With the switch arm swung up to the next contact some of the resistance is cut out, the current flow is greater and the armature is drawn into the next contact position connecting the loud speaker to receiving set B. In this manner the reproducer may be selectively connected to any one of the receiving sets. Switching the reproducer from one switch to another calls for no skill, but merely the moving of a switch from point to point.

If it is desired to always give the same station programs from the central station, the switch points may be marked with the station letters, so that the switch may be

5 moved to the station selected. If desired certain of the units can regularly receive 10 certain stations and others may be tuned at various times for stations giving particularly 15 good programs at the moment, at the discretion of the central station operator, depending on receiving conditions. It will be understood that any suitable amplification 20 may be provided in the receiving sets to take care of the large number of reproducers, which may be connected into the output 25 circuits. The individual reproducers may be provided with modulating or sound control devices, as is now customary with many reproducers on the market, so that the volume 30 of reproduction may be within the control of the user of the particular reproducer. This control would affect only his own reproducer. It will be noted that in order to 35 cut off reproduction, it is necessary to withdraw the plug from the jack and this withdrawal serves to break the circuit of the local battery and this avoids drain on this battery when the instruments are not being used.

30 We have shown one preferred form of construction for carrying out our invention, but it is obvious that other methods of remote control for a switching arrangement 35 may be substituted without otherwise modifying the invention and we contemplate such changes and modifications as come within the spirit and scope of the accompanying claims.

35 We claim:

1. In combination with a plurality of radio receiving sets, an external output circuit for each set, a plurality of radio re-

40 producers, a circuit for each reproducer, a battery and solenoid switch local to each reproducer circuit and a variable resistance in each reproducer circuit whereby the operation of the solenoid may be controlled and the reproducer circuit selectively connected to one of the receiving set output circuits. 45

2. In combination with a plurality of radio receiving sets, an external output circuit for each set, a plurality of radio reproducers, a circuit for each reproducer, a battery and solenoid local to each reproducer 50 circuit, a multiple switch operated by said solenoid, said switch having contacts connected to said reproducer circuit and other contacts connected to each of the receiver output circuits, and means adjacent said reproducer adapted to control the solenoid switch to selectively connect the reproducer to any one of the receiving sets. 55

3. In combination with a plurality of radio receiving sets, an external output circuit for each set, a plurality of radio reproducers, a circuit for each reproducer, a battery and solenoid local to each reproducer circuit, a multiple switch operated by said solenoid, said switch having contacts connected to said reproducer circuit and other contacts connected to each of the receiver output circuits; means to maintain the switch normally in the open position, and means adjacent the reproducer adapted to control 60 the solenoid switch to selectively connect the reproducer to any one of the receiving sets. 65

Signed at Denison, Crawford County, Iowa, this 12th day of January, 1926.
